UNITED STATES PATENT OFFICE.

HENRY ATWOOD GORHAM, OF BOSTON, MASSACHUSETTS.

STOP AND WASTE COCK.

SPECIFICATION forming part of Letters Patent No. 329,161, dated October 27, 1885.

Application filed April 3, 1885. Serial No. 161,106. (No model.)

To all whom it may concern:

Be it known that I, HENRY ATWOOD GORHAM, of Boston, (East Somerville,) in the county of Middlesex, of the Commonwealth of Massachusetts, have invented a new and useful Improvement in Stop and Waste Cocks; and I do hereby declare the same to be described in the following specification and represented in the accompanying drawings, of which—

10 Figure 1 is a side view, and Fig. 2 a longitudinal section, of a cock provided with my invention, the nature of which is defined in the claims hereinafter presented. Fig. 3 is a side view of the valve-stem and its valves as 15 separate from the body of the cock.

My improvement relates to the class of cocks that are provided with means of drawing water from the eduction-pipes after the closing of their valves upon their seats, such being to 20 prevent the pipe or pipes supplied through the cock from being burst by water freezing in them.

In the drawings, A represents the hollow body or case of the cock, it having within and 25 obliquely across its interior a partition, a, having a circular passage, b, extending through it in the part of it that is at right angles to the valve-stem, there being on the under side of such partition a seat, s, for the main valve 30 D. The said body is open at its ends, and there provided with female screws c c, for coupling the body to an induction-pipe, and also to an eduction-pipe. The said body is also open below the passage b, and has screwed 35 into the opening a cap, B, having within it concentrically a cylindrical chamber, d, from whose bottom a draining-passage, e, extends downward, and is or may be screw-threaded in its lower part to connect a drain-pipe to it. 40 At the upper end of the chamber d is an annular valve-seat, f, to co-operate with an auxiliary valve, g, fixed on the lower end of a short spindle, h, which at its upper end has a flange, i, extending from and around it. The 45 said auxiliary valve is fastened to its spindle by a headed screw, k, whose shank goes through the valve and screws into the spindle. Circumscribing the said spindle h is a screw-nut, l, that screws upon the lower part of the main 50 valve-spindle C, below the main valve D, fixed thereto, the screw m for receiving the valve and nut being a right-threaded one. The

spindle C is chambered in its lower part to receive the auxiliary spindle, and a spiral spring, E, for depressing it. At a suitable 55 distance above the main valve the spindle C is screw-threaded to screw into the top of the body or case A, the screw shown at t being a left-threaded one. A cup, G, screws on the upper part of the case A, and is to contain a 60 packing or washer to make a water-tight joint around the spindle C. The said spindle extends up through and somewhat above the said cap, and at its upper end the spindle is provided with a handle, H, fixed thereon. 65

When the cock is in use, the water enters the case and passes into the space o directly over the partition. On turning the main valve-stem to the right its valve D will be revolved with it and be moved downward away 70 from its seat, in order to allow the water to flow down through the partition and into the space p below it, and thence to the educt q of the cock.

While the main valve is close against its 75 seat the auxiliary valve will be off its seat a short distance, it being raised therefrom by the spindle C, drawing upward with it the screw-nut l, and causing such nut, by bearing against the flange i, to lift the auxiliary valve. 80 As soon, however, as the main valve is depressed from its seat, so as to let the auxiliary valve down upon its seat, the spring within the main-valve spindle will, by being contracted while the spindle further descends, bear or 85 keep the auxiliary valve down close upon its seat, and thereby prevent the escape of any water through the said seat. On the main valve being raised nearly up to its seat the auxiliary valve will be pulled upward and 90 will continue to rise until the main valve closes on its seat, from which it will be seen that when the main valve is closed on its seat whatever water may be in the pipe or pipes in advance of the main-valve seat will drain 95 therefrom through the auxiliary valve-seat.

I claim—

1. The combination of the cock body or case and its perforated partition, and the main valve and its spindle applied thereto, with 100 the draining-educt and its auxiliary valve-seat in the lower part of such case, and with the auxiliary valve, its flanged spindle, lifting screw-nut, and depressing-spring applied to

the main-valve spindle and the said auxiliary valve-seat, substantially as set forth.

2. The combination, with the cock body or case A, having in it the perforated partition 5 a, and with the main valve D, arranged below the partition, and having its spindle C provided with a screw, t, screwed into such case, of the cap B, screwed into the lower part of such case, and provided with the auxiliary valve-seat f, and its draining-educt, and of the auxiliary valve g, its flanged spindle h, lifting screw-nut l, and depressing-spring E, applied

to the main-valve spindle, and to operate with such auxiliary valve-seat, and the main-valve spindle, substantially as represented, the said case having, besides its draining-educt, an induct to lead water into the space above and an educt to discharge water from the space below the said partition, as explained.
